(57) **CLAIM**

The ornamental design for a pet sofa, as shown and described.

DESCRIPTION

FIG. 1 is a front perspective view of a pet sofa, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the pet sofa of FIG. 1, shown in a closed configuration; and,

FIG. 10 is an enlarged detail view of area 10 in FIG. 2. The broken lines in the drawings illustrate the portions of the pet sofa, which form no part of the claimed design.

The dot-dash-dash broken lines in FIGS. 2 and 10 show the boundaries of the enlargement shown in FIG. 10 and form no part of the claimed design.
